W. F. Amstutz

Attorney

UNITED STATES PATENT OFFICE.

ROBERT CARL RAHM, OF WYOMISSING, PENNSYLVANIA.

ROLL DEVICE FOR SPINNING MACHINES.

Application filed November 12, 1921. Serial No. 514,481.

To all whom it may concern:

Be it known that I, ROBERT CARL RAHM, a citizen of the United States, residing at Wyomissing, in the county of Berks and State of Pennsylvania, have invented certain new and useful Improvements in Roll Devices for Spinning Machines, of which the following is a specification.

My invention relates to roll-feed devices adapted more particularly for thread doubling and twisting machines, the main objects being to provide for automatically spacing and evenly tensioning threads or strands passed thereover to receiving mechanism. The invention is fully described in connection with the accompanying drawing illustrating a preferred embodiment thereof, and is clearly defined in the subjoined claims.

Fig. 1 is an end view of a mounted pair of feed rolls embodying my invention; an ordinary drive gear and a supporting standard therefor being indicated.

Fig. 2 is a corresponding plan view of my improved device.

Fig. 3 indicates a simple modification of the roller arrangement.

It is customary in the class of machines referred to, to pass threads or strands from supply spindles to winding means over intermediate feed rolls, and as my invention relates exclusively to an improved arrangement of rolls adapted to such use, the associated parts of known mechanism in connection with which it is usable is sufficiently indicated by the showing of a supporting standard 5 for the rolls and a drive shaft 6 and gear 7 for the latter.

The main function of such a roll device is the feeding of the threads delivered thereto, with a minimum of friction and with uniform tensioning tending to avoid breakage; and my invention aims to accomplish this in a simple and effective manner.

To this end I utilize in a novel way the well known "climbing" tendency of a belt or cord running on an inclined pulley surface. Each of the two rolls 10, 10^a, as shown, is provided as heretofore with a pinion, 11 or 11^a, and with axles or trunnions 12, 12^a mounted in a frame 13 suitably carried by the standard 5, said pinion being arranged in mesh with said drive gear 7; the threads from determined spindles being passed as a single strand, and in a series of convolutions as desired, around the two pul-

leys and thence to the twisting mechanism, as indicated.

In my improved construction illustrated, all the axle bearings are arranged in the same plane, but are so spaced as to mount the shafts convergingly. Also, each of the rolls is tapered, as indicated, with their larger-diameter ends located adjacent the converging ends of the axles and their smaller-diameter ends adjacent the wider-spread ends thereof. The increase in the diameter of the rolls at the axle-converged ends is preferably made sufficient, as indicated, to neutralize the greater spread of the axles at the opposite end so as to make the convolutions of thread upon the two rolls equal at different points in the lengths of the rolls; that is, the sum of the two half-circumferences of the rolls and of twice the spacing apart of the axles, is made equal at all points in the length of the rolls.

The effect of this combination of convergingly arranged axles and tapered rolls thereon, is to maintain a uniform spacing apart of any desired number of convolutions of the thread upon the two rolls, and a uniform tensioning of the thread.

The spaced turns or convolutions of thread upon the rolls are made to be of equal length, a convolution received, through guide-eye 15, upon the take-on end of the rolls, remains at the same length as it travels towards the let-off end of the rolls, thus avoiding slackening or tightening; and the converging of the axles enables a determined automatic spacing apart of the convolutions to be secured with a small tapering of the rolls,

so that the slight slippage incident to such tapering is minimized. The described proportioning of the convergency of the axles and the tapering of the rolls insures most satisfactorily the avoidance of thread breakage, but their proportions may be varied

without seriously impairing the effect of my improved construction, and the roll taper which neutralizes the lengthening of the convolutions at the wide-spread axle portions may be provided upon one of the rolls as indicated in Fig. 3 instead of being

equally divided upon the two rolls as in the preferred construction particularly described, which may be otherwise modified within the scope of my invention as defined in the claims.

What I claim is:

1. A roll-feed device comprising a pair of

jointly driven equally tapered rolls mounted upon converging axles with their oppositely arranged larger-diameter ends closer spaced than their smaller-diameter ends.

2. A roll-feed device comprising a pair of jointly driven equally tapered rolls mounted upon converging axles, the taper of the rolls being arranged to neutralize the spread of the converging axles and equalize convolutions of thread thereon.

3. A roll-feed device comprising jointly

driven rolls mounted upon converging axles, the combined peripheries of the rolls at the converging ends of the axles being greater than at the spread ends thereof.

4. A roll-feed device comprising jointly driven rolls mounted upon converging axles, the combined peripheries of the rolls at the converging ends of the axles being so much greater than at the spread ends thereof as to equalize convolutions of thread thereon.

In testimony whereof I affix my signature.
ROBERT CARL RAHM.
